UNITED STATES PATENT OFFICE

MAURITZ VOS AND TORBEN LAURENT, OF STOCKHOLM, SWEDEN, ASSIGNEES TO TELEFONAKTIEBOLAGET I. M. ERICSSON, OF STOCKHOLM, SWEDEN, A COMPANY OF SWEDEN

ELECTRICAL NETWORK

Application filed November 14, 1930, Serial No. 495,746, and in Sweden November 18, 1929.

The present invention relates to an impedance network. More particularly the invention relates to such networks used in telephone lines and in lines for multiple traffic with high frequency currents, the network having then for its purpose to separate currents of different frequencies or of different directions of propagation. In lines having repeaters the network may be used in connection with differential transformers and balancing networks to eliminate reflection disturbances.

The network according to the invention is arranged in so called bridged T-connection, i. e. it consists of a shunt inductance and series inductances symmetrically connected in relation thereto which latter inductances two and two are bridged by bridging impedances. The impedances included in the network form, according to the invention, two filter chains said series inductances forming a common part of said two filter chains which each are provided with a couple of free external terminals. One of the filter chains comprises also the shunt impedance whereas the other filter chain comprises the bridge impedance or impedances. The characteristics of the two filters at the internal terminals, i. e. those connected in the network, are adjusted to suit each other and the line characteristic in a particular manner described below.

Although the network operates as a filter chain in its entirety, it is, however, by mutual and suitable adjustment of the filter chains rendered possible to make the input and the output impedances of the network independent of the frequency in the neighbourhood of the limiting frequencies of the two filter chains. Said property is of great importance as it renders possible a reflectionless connection to the network operating as a filter chain which hitherto has not been possible.

The invention relates also to special embodiments of the filter chains included in the network and certain arrangements and combinations of several similar networks to obtain the best possible utilization of the incoming energy.

In the application of the invention for multiple traffic in the telegraphy and the telephony while using high-frequency carrier waves, several networks corresponding to different talking connections may, according to the invention be connected in cascade, separate sending or receiving apparatus being then connected to the external terminals of both filters in each part network. Also the network composed in this manner may, independently of the number of part networks connected in cascade, be adjusted to make the line reflectionless.

The invention will be more closely described with reference to the accompanying drawings which show a number of different embodiments. Figure 1 shows diagrammatically an embodiment of the network in unsymmetrical bridged T-connection. Figures 2 and 3 show the two filter chains included in the network according to Figure 1 and separated from each other. Figure 4 shows a connection corresponding to the one in Figure 1 but symmetrically formed. Figure 5 shows two filter chains of which the net has to be built. Figure 6 shows two impedances corresponding to each other in the two filter chains in Figure 5. Figure 7 shows a special embodiment of the impedances in Figure 6. Figure 8 shows an embodiment of the invention in which a differential transformer is included. Figure 9 shows diagrammatically the connection of a two-way amplifier which is provided with networks according to the invention. Figure 10 shows a part of a two-way amplifier as carried out in practice. Figure 11 shows a network according to the invention. Figures 12 to 15 show other embodiments of the network and Figure 16 is a circuit diagram of a sending and receiving set for highfrequency and lowfrequency signals. The plant comprises a number of networks connected in cascade according to the invention. Figure 17 shows an embodiment of a connection between a two-wire line and a loaded or pupinized quad wire connection, the two talking paths in the quad wire connection being used for mutually opposite talking directions. Figure 18 shows another embodiment.

ment of such a connection the two lines in the quad wire connection being parallel connected and forming together a single talking path.

- 5 The network according to Figure 1 arranged in unsymmetrical bridged T-connection comprises the shunt inductance 17, the two series impedances 11, 12 connected symmetrically in relation to the shunt impedance, and the bridge impedance 18 shunted across the two series impedances. From an electrical point of view the network is composed of two filter chains A, B which are shown individually in Figures 2 and 3. In 10 the filter chains the two series impedances 11, 12 form a common part. The filter chain A comprises, in addition to said series impedances, the shunt impedance 17 and the filter chain B comprises, besides the series 15 impedances 11, 12, the bridge impedance 18 connected in shunt thereto. The network is provided with input and output terminals 1, 2 and 3, 4 and the connections between said two terminal couples may be considered 20 as forming two through-going lines *a*, *b*. The two filter chains A, B are each provided with one couple of external terminals 7, 8 and 5, 6 respectively for the connection of branch lines or apparatus or the like, by 25 way of example sending and receiving sets. The terminals 7, 8 of the filter chain A are disposed on the shunt impedance 17, and the terminals 5, 6 of the filter chain B are disposed on the bridge impedance 18. The two 30 terminal couples *c*, *d* and *e*, *f* of the two filter chains may be considered as junction points. The one *c* of the internal terminals of the filter chain A is an imaginary junction point which may be conceived as formed by connecting together the external ends of the 35 parallel connected series impedances 11, 12. The other *d* of the internal terminals of the filter chain A is formed by the middle point of the line *b*. The internal terminals of the 40 filter chain B may be considered as coinciding with the terminals 1, 3 of the network.

When carrying out the invention in practice impedances of equal sizes, such as lines or line sections, are generally connected to 45 the two terminal couples 1, 2 and 3, 4 respectively. As will be shown in the following it is possible, by a suitable arrangement of the two filter chains A, B, to manage that the input and output characteristics of the 50 networks, thus the characteristics at the terminals 1, 2 and 3, 4, will be equal both in relation to each other and in relation to the impedances connected thereto so as to avoid reflections at the terminals.

55 The following designations are introduced.

X_1 = the impedance of the filter chain A between the terminals *c* and *d*.

X_2 = the impedance of the filter chain B between the terminals *e* and *f*.

K = an impedance connected into circuit between the terminals 1 and 2.

The input impedance between the terminals 3 and 4 may be expressed as follows:

$$Z = \frac{4X_1(X_2 + K) + X_2 \cdot K}{4(X_2 + K) + X_2} \quad (1)$$

If now

$$\sqrt{X_1 \cdot X_2} = K \quad 75$$

we obtain according to Equation 1

$$Z = K = \sqrt{X_1 \cdot X_2} \quad (2)$$

It is now assumed that the one filter chain, 80 by way of example A, counted from the internal terminals *c*, *d* begins with a half filter chain having a T-characteristic whereas the other filter chain, by way of example B, counted from the terminals *e*, *f* begins 85 with a half filter chain of the opposite type, thus having π -characteristic as shown in Figure 5. Each of the two filter sections consists of two impedances x_3 , x_4 and y_3 , y_4 the input impedance between the terminals *c*, *d*, 90 ($\mathbf{T}$ -characteristic) being equal to Z_1 and the input impedance between the terminals *e*, *f* (π -characteristic) being equal to Z_2 . The half $\mathbf{T}$ -section consists of a series impedance $X_4 = S_1/2$ and a shunt impedance $X_3 = 2A_1$, 95 and the half π -section consists of a series impedance $y_3 = S_2/2$ and a shunt impedance $y_4 = 2A_2$. The characteristics Z_1 , Z_2 have the following values.

$$Z_1 = \sqrt{S_1 \cdot A_1} \cdot \sqrt{1 + \frac{S_1}{4A_1}} \quad (3)$$

$$Z_2 = \sqrt{\frac{S_2 \cdot A_2}{1 + \frac{S_2}{4A_2}}} \quad (4) \quad 105$$

For the sake of simplicity the following abbreviations are introduced.

$$R_1 = \sqrt{S_1 \cdot A_1} \quad 110$$

$$\rho_1 = \sqrt{1 + \frac{S_1}{4A_1}}$$

$$R_2 = \sqrt{S_2 \cdot A_2} \quad 115$$

$$\rho_2 = \sqrt{1 + \frac{S_2}{4A_2}}$$

The following expressions are then obtained. 120

$$Z_1 = R_1 \cdot \rho_1 \quad (3')$$

$$Z_2 = \frac{R_2}{\rho_2} \quad (4') \quad 125$$

When the filter chains A, B are terminated reflectionless their input impedances X_1 , X_2 are equal to the input characteristics Z_1 , Z_2 and the input impedance of the networks 130

at the terminals 3, 4 becomes then according to (2)

$$Z = \sqrt{R_1 \cdot \rho_1 \cdot \frac{R_2}{\rho_2}} \quad (5)$$

According to the invention filters are used in which the products of series and shunt impedances in a filter section are independent of the frequency which is the case, by 10 way of example, when S_1, S_2 are purely inductive impedances and A_1, A_2 purely capacity impedances. In the above formula 3, 4 the products A_1, S_1 and A_2, S_2 and thus also the two root expressions R_1, R_2 are then constant. In the two root expressions ρ_1 and ρ_2 the frequency is however included. If it is 15 possible to eliminate said two root expressions from the formula of the network impedance according to (5) said impedance will be independent of the frequency. Said 20 result may be obtained by selecting the series impedances and the shunt impedances of the filter chains A, B in such a manner that

$$\begin{aligned} 25 \quad \frac{A_1}{S_1} &= \frac{A_2}{S_2} \\ \text{thus} \quad \rho_1 &= \rho_2 \end{aligned} \quad (6)$$

According to the Formula (5) we obtain 30

$$Z = \sqrt{Z_1 Z_2} = \sqrt{R_1 R_2} \quad (7)$$

The input impedance of the network will thus be constant and equal to a purely ohmic 35 resistance.

It is not necessary that the two filter chains directly begin with a T-section or a π -section. There are filters, by way of example according to the Swedish patent application No. 965/28 which may have T- or π -characteristic without externally appearing as beginning with a T-section or a π -section.

Besides the condition that the two filter 45 chains A and B should have opposite characteristics at their internal terminals it is assumed, according to the theory of filter chains, that the two filter chains have the same limiting frequency. The condition 50 that the filter chains terminate reflectionless must not always be complied with which will be explained in the following with reference to Figure 5.

Under said conditions also the input impedance of the network is independent of the 55 frequency also in the neighborhood of the limiting frequency of the two filter chains. When this result is obtained one may easily, by the addition of suitable impedances, 60 obtain an input impedance which is variable with the frequency if this is desirable, by way of example, when the network is connected to a line, of which the characteristic varies in a certain manner with the frequency.

Between the different terminal couples of the network different filter effects may be obtained. Between the input and output sides of the network, i. e. between the terminal couples 1, 2 and 3, 4 all the oscillations 70 within the range of frequencies of the network are suppressed. The network operates thus between said terminal couples as a band suppressing filter. Between one of said terminal couples, by way of example 1, 2, and 75 3, 4 one of the external terminal couples 5, 6 or 7, 8 respectively of the network the ordinary band filter effect is obtained and between the two external terminal couples 5, 6 and 80 6, 8 of the two filter chains all frequencies are suppressed.

The embodiment according to Figure 4 is equivalent with that shown in Figure 1 and is differentiated from the latter only 85 therein that the two throughgoing lines a, b of the network are mutually equal, as the filter chain B is substituted by two filter chains D, E which each are connected into one of the two lines a, b . Each one of the two filter chains D, E is in similarity with 90 the filter chain B in Figure 1 composed of two equal series impedances 13, 14 and 15, 16 respectively and a bridge impedance 19 and 20 respectively. The external terminal couples of the filter chains D, E corresponding 95 to the terminals 5, 6 in Figure 1, are designated 5, 6 and 9, 10 respectively. The network C comprises in this case, besides the shunt impedance 21, the two parallel connected series impedances 13, 14 and 15, 100 16.

Figure 5 shows an embodiment of the filter chains of the network. The filter chain B is provided on its output side with a terminal impedance R_2 and includes a series impedance y_1 connected thereto whereupon, counted in the direction towards the input side, shunt impedances $y_2, y_3, \dots$ alternate with series impedances $y_3, \dots$. The input 105 terminals of the filter chain B are designated e, f . The filter chain A is terminated in similar manner with an impedance R_1 and comprises, counted in the direction towards the terminals c, d , shunt impedances $x_1, x_3, \dots$ alternating with series impedances $x_2, x_4, \dots$. The terminal impedances 110 R_1, R_2 are so dimensioned that 115

$$\sqrt{R_1 R_2} = k$$

where k designates a constant. The impedances $x_1, x_2, \dots$ and $y_1, y_2, \dots$ respectively included in the two filter chains are so selected that the geometrical mean value of each impedance x_n in the one filter chain and the impedance y_n having the corresponding number n , counted from the output terminals in the other filter chain, is also equal to k , i. e.

$$\sqrt{x_1 \cdot y_1} = \sqrt{x_2 \cdot y_2} = \sqrt{x_3 \cdot y_3} = \sqrt{x_n \cdot y_n} = k. \quad 130$$

If one imagines the building up of the two networks by gradually adding the different impedances x, y to the terminal impedances R_1, R_2 , the mutually corresponding impedances being then each time added to both filter chains, we find that the geometrical mean value of the input impedances in the two gradually growing filter chains will all the time maintain the value k . If one thus first adds the series impedance x_1 to R_1 and the shunt impedance to y_1 to R_2 the geometrical mean value of the two impedances thus formed is equal to

$$15 \quad \sqrt{(Z_A + x_1) \frac{1}{\frac{1}{Z_B} + \frac{1}{y_1}}} = \sqrt{(Z_A + x_1) \frac{1}{\frac{Z_A}{k^2} + \frac{x_1}{k^2}}} = k.$$

If now the impedances x_2 and y_2 respectively are added one finds in similar manner that the products of the two composed impedances still equals k^2 . This is apparently the case independently of the number of the gradually added filter chain sections. In composing the two filter chains A, B in such a manner that the geometrical mean value of their input impedances represent a certain constant value k it has only to be observed that the impedances two and two comply with the above mentioned condition.

30 A similar reasoning may be used concerning the composition of each of the impedances x_1, x_2 etc., and y_1, y_2 etc., respectively. Figure 6 shows diagrammatically how the impedances x and y may be composed in order to comply with the corresponding condition. Each shunt connection of two impedances in x , by way of example a_1 and a_2 , corresponds to a series connection of two corresponding impedances b_1 and b_2 in y and vice versa. If now the part impedances a_1, a_2, a_3 etc. and b_1, b_2, b_3 etc., respectively in the two impedances x, y now are selected in such a manner that

$$\sqrt{a_1 b_1} = \sqrt{a_2 b_2} = \sqrt{a_3 b_3} = k$$

45 one finds, by exactly the same reasoning as above, that the geometrical mean value of impedances x, y , composed in this manner is equal to k . The simplest manner to comply with said condition for the composition of x and y is to arrange the part impedances a, b in such a manner that in each couple of part impedances a_1, b_1 etc. the one part impedance consists of a capacity C and the other part impedance of an inductance L in which case one selects

$$\sqrt{a \cdot b} = \sqrt{\frac{1}{j\omega C} \cdot j\omega L} = \sqrt{\frac{L}{C}} = k$$

60 or else may the two part impedances in each impedance couple a, b consists of ohmic resistances r_1 and r_2 which have to be selected in such a manner that

$$\sqrt{r_1 r_2} = k.$$

65 If all the part impedances a, b are formed

by capacities and inductances they must have the smallest possible losses because otherwise the condition of the dimensioning cannot be exactly complied with. The error caused by the loss resistance may, however, be reduced to a very low value if the geometrical mean value of the loss resistances in each couple of impedances is selected equal to k because then the condition for the dimensioning will be exactly complied with also for those frequencies at which the resonance occurs and the loss resistance is at most pronounced.

70 Figure 3 shows two mutually corresponding part impedances x, y each composed of a capacity C_x and C_y respectively, and of an inductance L_x and L_y respectively, and of a resistance r_x and r_y respectively. Provided the loss resistance is disregarded, the capacities and inductances are as mentioned 75 so selected that

$$\sqrt{\frac{L_x}{C_y}} = \sqrt{\frac{L_y}{C_x}} = k.$$

In resonance

$$x \sim \frac{L_x}{r_x C_x} \text{ and } y = r_y.$$

To make the geometrical mean value of x and y equal to k also at resonance one must select

$$r_y \cdot \frac{L_x}{r_x C_x} = k^2 = \frac{L_y}{C_x}$$

or

$$\frac{r_x}{L_x} = \frac{r_y}{L_y}$$

In order to make the influence of the loss resistances upon the conditions for the dimensioning so small as possible also the loss angles of the inductances L_x, L_y must thus be equal which may be obtained, by way of example, by providing the inductances with equal iron cores and equally large winding spaces.

In the deduction of the formula (7) the assumption is made that the input impedances X_1, X_2 between the terminals c, d and e, f respectively in the filter chains in Figure 5 coincide with the characteristics Z_1, Z_2 between the same terminals, i.e. that the filter chains terminate reflectionless in terminal impedances dimensioned in corresponding manner.

In practice it is of course difficult to design suitable terminal impedances which at all frequencies terminate the filter chains reflectionless. A condition for this is that the terminal impedances for all frequencies are equal to the output characteristics of the filter chains. The desired result that the input impedance of the network should be independent of the frequency may then, however

as explained below, also be obtained without terminating the filter chains in this manner reflectionless.

The input characteristic of the two filter chains A, B in Figure 5 may, according to the Equation 3', 4', be expressed in the following manner:

$$Z_1 = R_1 \cdot \rho_1$$

$$Z_2 = \frac{R_2}{\rho_2}$$

As before it is assumed that

$$\rho_1 = \rho_2 = \rho$$

15 In the same manner one obtains for the output characteristic of the two filter chains at the terminals 5, 6 and 7, 8 the values

$$\frac{R_1}{\rho} \text{ and } R_2 \cdot \rho$$

20 respectively.

On the output side of the filter chains, i. e. at the terminals 7, 8 and 5, 6 respectively terminal impedances are connected which are equal to R_1 and R_2 respectively.

25 β_1 = the attenuation of each filter section in the filter chain A.

β_2 = the attenuation of each filter section in the filter chain B.

30 α_1 = the line angle for each filter section in the filter chain A.

α_2 = the line angle for each filter section in the filter chain B.

p_1 = the reflection attenuation constant of the filter chain A.

35 p_2 = the reflection attenuation constant of the filter chain B.

q_1 = the reflection line angle of the filter chain A.

40 q_2 = the reflection line angle of the filter chain B.

n_1 = the number of filter sections of the filter chain A.

n_2 = the number of filter sections of the filter chain B.

45 The absolute values of the input impedances of the two filter chains A, B at the terminals c, d and e, f respectively will be (compare "Elektrische Nachrichtentechnik" volume 5, Number 5, 1928, "Ueber das Nebensprechen und andere damit zusammenhängende Erscheinungen", Laurent)

$$(X_1) = (Z_1) \sqrt{\frac{\cosh 2(\beta_1 n_1 + p_1) - \cos 2(\alpha_1 n_1 + q_1)}{\cosh 2(\beta_1 n_1 + p_1) + \cos 2(\alpha_1 n_1 + q_1)}}$$

$$55 (X_2) = (Z_2) \sqrt{\frac{\cosh 2(\beta_2 n_2 + p_2) - \cos 2(\alpha_2 n_2 + q_2)}{\cosh 2(\beta_2 n_2 + p_2) + \cos 2(\alpha_2 n_2 + q_2)}}$$

The phase angles of the impedances are

$$60 \Phi_{X_1} = \Phi_{Z_1} + \arctg \frac{\sin 2(\alpha_1 n_1 + q_1)}{\sinh 2(\beta_1 n_1 + p_1)}$$

$$\Phi_{X_2} = \Phi_{Z_2} + \arctg \frac{\sin 2(\alpha_2 n_2 + q_2)}{\sinh 2(\beta_2 n_2 + p_2)}$$

65 If one now makes $\beta_1 \cdot n_1 = \beta_2 \cdot n_2$ and $\alpha_1 \cdot n_1 =$

$\alpha_2 \cdot n_2$, by way of example, by making the filter chains with the same propagation constant for each filter section and the same number of filter sections, whereby

$$\left. \begin{aligned} \alpha_1 &= \alpha_2 = \alpha \\ \beta_1 &= \beta_2 = \beta \\ n_1 &= n_2 = n \end{aligned} \right\}$$

70

where n is an even or an odd number. As is readily understood from the above mentioned article in "Elektrische Nachrichtentechnik" we further have

$$e^{2(p_1 + jq_1)} = \frac{\frac{R_1}{\rho} + R_1}{\frac{R_1}{\rho} - R_1} = \frac{1 + \rho}{1 - \rho} \quad 80$$

$$e^{2(p_2 + jq_2)} = \frac{R_2 \cdot \rho + R_2}{R_2 \cdot \rho - R_2} = \frac{1 + \rho}{1 - \rho} \quad 85$$

Thus is

$$e^{2(p_1 + jq_1)} = -e^{2(p_2 + jq_2)}$$

and

$$\left. \begin{aligned} e^{2p_1} &= e^{2p_2} \\ e^{2jq_1} &= -e^{2jq_2} \end{aligned} \right\} \quad 90$$

This means that

$$p_1 = p_2 = p \text{ and } q_1 = q_2 + \frac{\pi}{2} = q \quad 95$$

If said values in the above expressions are inserted for the absolute value of the input impedances one obtains

$$(X_1) = (Z_1) \sqrt{\frac{\cosh 2(\beta n + p) + \cos 2(\alpha n + q)}{\cosh 2(\beta n + p) - \cos 2(\alpha n + q)}} \quad 100$$

$$(X_2) = (Z_2) \sqrt{\frac{\cosh 2(\beta n + p) - \cos 2(\alpha n + q)}{\cosh 2(\beta n + p) + \cos 2(\alpha n + q)}} \quad 105$$

and, upon the insertion in the expression for the phase angle of the impedances,

$$\Phi_{X_1} = \Phi_{Z_1} - \arctg \frac{\sin 2(\alpha n + q)}{\sinh 2(\beta n + p)} \quad 110$$

$$\Phi_{X_2} = \Phi_{Z_2} + \arctg \frac{\sin 2(\alpha n + q)}{\sinh 2(\beta n + p)}$$

If the geometrical mean $\sqrt{X_1 \cdot X_2}$ is calculated from the Formula (2) the absolute value of the input impedances

$$(Z) = \sqrt{(X_1) \cdot (X_2)} = \sqrt{(R_1 \rho) \cdot \left(\frac{R_2}{\rho}\right)} = \sqrt{(R_1) \cdot (R_2)} \quad (8) \quad 120$$

For the phase angles Φ_Z of the input impedances one obtains, if Φ_{R_1} , Φ_{R_2} and Φ_p are the phase angles of the quantities R_1 , R_2 and ρ ,

$$\frac{1}{2}(\Phi_{R_1} + \Phi_p + \Phi_{R_2} - \Phi_{R_1}) = \frac{1}{2}(\Phi_{R_1} + \Phi_{R_2}) = 0.$$

$$\Phi_Z = \frac{1}{2}(\Phi_{X_1} + \Phi_{X_2}) = \frac{1}{2}(\Phi_{Z_1} + \Phi_{Z_2}) =$$

The quantity Z acts thus, as in the previous case, as an ohmic resistance. The re-

125

128

sult involves that the reflections which are represented by p_1 , p_2 and q_1 , q_2 compensate each other in the geometrical mean

$$5 \quad \sqrt{X_1 \cdot X_2},$$

provided the filter chains are terminated by R_1 , R_2 .

Figure 8 shows an embodiment of a network which includes a differential transformer and is arranged in symmetrically bridged T-connection. The one H of the two filter chains consists of the shunt impedance 17 and the primary winding of the differential transformer. The primary

10 winding consists of four coils L_1 , L_2 , L_3 , L_4 , wound on the same magnet core and mutually tightly coupled and two and two series connected, the two coil couples being each included in one of the two lines

15 a , b of the network. The shunt impedance 17 is connected between the middle points of the two coil couples. On account of the tight magnetic coupling in the transformer said transformer introduces no self induction and no iron losses but only as small direct current resistance in the filter chains. The filter chain I comprises both the primary coils L_1 to L_4 and the secondary winding L_5 in the differential transformer

20 and also the bridge impedance 18 connected to the terminals of the secondary windings. The filter chain I is connected over the differential transformer in the same manner to the two lines a , b of the network whereby

25 the symmetry of the connection is obtained. Said network may be advantageously used in two-way amplifiers or the like, a line or a line section being connected to the terminals 3, 4 and a corresponding line balance to the terminals 1, 2. To the external

30 terminal couples 5, 6 and 7, 8 of the two filter chains I, H may, if desired, one sending circuit and one receiving circuit, or the amplifier circuits each corresponding to one talking direction of a repeater, be connected.

Figure 9 shows diagrammatically an embodiment of a two way amplifier according to the invention. To the terminal couples g , h , and i , j the lines or line sections may

35 be connected. The corresponding line balances are designated N_1 , N_2 . Two amplifiers V_1 , V_2 each for one talking direction are connected over differential transformers T_1 and T_2 and over filter chains K_1' , K_1'' ,

40 K_2' , K_2'' connected to the lines. The filter chains K_1'' , K_2' form together with the differential transformer T_1 a network according to the invention and the filter chains K_1' , K_2'' form together with the differential transformer T_2 another similar network.

45 As seen from the figure the filter chains K_1'' , K_2' , on the sides facing the differential transformer T_1 , have T-characteristic and π -characteristic respectively and, on the op-

posite sides, also T-characteristic and π -characteristic respectively. The two filter chains on the opposite side of the amplifier are arranged in similar manner. In this disposition the two filter chains have thus in each of the networks by way of example K_1'' and K_2' mutually different characteristics on both sides. The two filter chains have also the same number of half filter sections which number may be even as well as odd.

50 Figure 10 shows a practical embodiment for the application of the invention in a two-way amplifier. In the figure only such parts are shown which are necessary for the understanding of the circuit arrangement.

55 The arrangement comprises two amplifier valves V_1 , V_2 , one for each talking direction. The talking directions are indicated by arrows. The anode side of the valve V_1 and the grid side of the valve V_2 are connected over corresponding filter chains to the differential transformer T .

60 The filter chain connected to the valve V_1 comprises, besides the differential transformer, on the one hand a coil L_a connected in series with the secondary winding of the differential transformer and, on the other, a condenser C_a bridging the primary winding of the transformer.

65 In the filter chain connected to the amplifier valve V_2 there are, besides the differential transformer common to both filter chains, included a coil L_g connected to the middle point of the primary winding and a condenser C_g connected in series there-

70 to. If the differential transformer, as assumed, has a very tight coupling between the two windings, a high no load impedance, and small direct current resistances, or in other words, if it acts as a so called ideal

75 transformer it will have no influence upon the electrical properties of the filter chains.

80 To the input terminals g , h of the network the line incoming on the one side of the two-way amplifier is connected. To the op-

85 posite terminals of the network a corresponding line balance N is connected. Between the valve V_2 and the appertaining filter chain an input transformer T_1 having a comparatively high primary impedance is

90 connected into circuit. The oscillations incoming from the line over the terminals g , h are supplied to the input transformer T_1 over the corresponding filter chain and a potentiometer P connected to the output terminals of the filter chain.

95 As seen from the figure the filter chain lying between the line and the anode side of the valve V_1 has, on the side facing the terminal couple g , h , a π -characteristic whereas the other filter chain on the side facing said terminal couple

100 has a T-characteristic. Between the valve V_1 and the appertaining filter chain an input transformer T_2 having a comparatively high primary impedance is connected into circuit.

105 The oscillations incoming from the line over the terminals g , h are supplied to the input transformer T_2 over the corresponding filter chain and a potentiometer P connected to the output terminals of the filter chain.

110 As seen from the figure the filter chain lying between the line and the anode side of the valve V_2 has, on the side facing the terminal couple g , h , a π -characteristic whereas the other filter chain on the side facing said terminal couple

115 has a T-characteristic. Between the valve V_2 and the appertaining filter chain an input transformer T_1 having a comparatively high primary impedance is connected into circuit.

120 The oscillations incoming from the line over the terminals g , h are supplied to the input transformer T_1 over the corresponding filter chain and a potentiometer P connected to the output terminals of the filter chain.

125 As seen from the figure the filter chain lying between the line and the anode side of the valve V_1 has, on the side facing the terminal couple g , h , a π -characteristic whereas the other filter chain on the side facing said terminal couple has a T-characteristic.

130 As an example of the practical application of an arrangement according to the invention the dimensioning of the above described amplifier according to Figure 10 is given.

- The following designations are introduced:
 R_a = the anode resistance of the valve V_1 .
 R_p = the entire potentiometer resistance P .
 L_1 = the inductance of the coil L_1 .
 L_2 = the inductance of the coil L_2 .
 C_1 = the capacity of the condenser C_1 .
 C_2 = the capacity of the condenser C_2 .
 n = the ratio of the differential transformer T .

- 10 B = the impedance of the line balance N .

Because the filter chain connected to the valve V_1 corresponds to the filter chain A in Figure 5 and the filter chain connected to the grid side of the valve V_2 corresponds to B , the anode resistance R_a is in the present case evidently a parallel to the terminal impedance R_1 whereas the potentiometer resistance R_p corresponds to the terminal impedance R_2 in Figure 5, providing the primary winding of the input transformer T_1 has a high impedance. For the series and shunt impedances of the filter chains in the arrangement in Figure 10 the following equations are valid.

$$25 \quad S_1 = j\omega L_1$$

$$A_1 = \frac{1}{j\omega C_1 n^2}$$

$$30 \quad S_2 = j\omega L_2$$

$$A_2 = \frac{1}{j\omega C_2}$$

From this follows

$$35 \quad R_a = \sqrt{S_1 A_1} = \sqrt{\frac{L_1}{C_1 n^2}} = \frac{1}{n} \cdot \sqrt{\frac{L_1}{C_1}}$$

$$R_p = \sqrt{S_2 A_2} = \sqrt{\frac{L_2}{C_2}}$$

- 40 The condition (6) may in this case be expressed as follows

$$L_1 C_1 n^2 = L_2 C_2.$$

- 45 The impedance of the line balance N must obtain the following value in order to suit the line, of which the characteristic is related to R_a , R_p as indicated in Equation (8) :

$$B = \sqrt{R_a R_p}$$

- 50 The three first conditions may immediately be complied with. The fourth condition may immediately be complied with for free overhead lines and weekly loaded cable lines and may in other cases be met by a suitable line extension.

Figure 11 shows an embodiment of the network according to Figure 1. The filter chain B includes, counted from the external terminals 5, 6, a series capacity composed of two series connected capacities C_{B1} the secondary winding L_B of a transformer T , of which the primary winding L_m divided into two equal parts forms the common part of both filter chains, and finally

a capacity shunted to the primary winding L_m and consisting of two series connected condensers C_{T2} . The filter chain A includes, counted from the output terminals 7, 8, a 70 shunt condenser C_{A1} a transformer T_A and a condenser C_{A2} connected in series with the primary winding of the transformer, and finally the two winding halves of the primary winding L_m of the transformer T in 75 parallel connection. As may be seen from the figure the parallel connection of capacity and inductance in the one network corresponds to a series connection of inductance and capacity in the other network. To obtain the best possible energy utilization the network is so dimensioned that the impedance of the network at each one of the terminal couples 1, 2 and 3, 4 is equal to k , between the external terminals 5, 6 of the filter 80 chain B equal to $2k$, and between the external terminals 7, 8 of the filter chain A equal to $\frac{k}{2}$. The impedances of the apparatus connected to the terminals 5, 6 and 7, 8 must 85

also be equal to $2k$ and $\frac{k}{2}$ respectively. The oscillation energy, having frequencies within the range of frequencies of the filter chains and introduced at the input terminals 1, 2 of the network, distributes itself according to the terminal impedances $2k$ and $\frac{k}{2}$ respectively

90 connected to the external terminals of the two filter chains whereas, on the other hand, the voltage between the output terminals 3, 4 of the network will be zero at said frequencies. The network operates thus between the terminals 1, 2 and 3, 4 as a band suppression 100 filter. If the voltage between the terminals 1, 2 is V , the voltage between the terminals 5, 6 will be equal to V and between the terminals 7, 8 equal to $\frac{V}{2}$. Strictly speaking this 110 is, however, correct only for the middle frequency of the frequency range and at ratios of 1:1 of the two transformers T_A , T .

115 In the embodiment according to Figure 11 is it generally possible to utilize only the energy received at the external terminals 5, 6 and 7, 8 of one of the filter chains A or B , i. e. only one half of the supplied energy. A complete utilization of the energy supplied may, on the other hand, be obtained in the embodiment according to Figure 12 which is differentiated from the connection in Figure 11 in that the output sides of the two filter chains A , B are parallel connected. Said parallel connection is rendered possible without loss of energy by that the ratios of the two transformers are so selected that the voltages on the output side of the transformers are mutually equal. The ratio of the 120 125 130 135 140 145 150

transformer T_A , counted from the output terminals, will be, by way of example, selected half as high as the ratio in the transformer T . It must, of course, be observed that the connecting together must be made so that the two voltages have the same phase. In the connection shown in Figure 12 of the terminals 5, 6 and 6, 8 it is assumed that the primary and secondary windings of the 16 transformers are wound in the same directions.

If the ratio μ_A of the transformer T_A is equal to 1:2 and the ratio μ of the transformer T is made equal to 1:1 the output voltage for each transformer, i. e. the voltages at the terminals 5, 6 and 7, 8 will be equal to the supplied voltage V between the terminals 1, 2. The network impedance at the parallel connected terminal couples is

$$\frac{2k \cdot 2k}{2k + 2k} = k$$

Figure 13 shows a similar arrangement for utilizing the entire energy supplied to the input terminals 1, 2 of the network and is differentiated from that in Figure 12 substantially therein that the output sides of the two filter chains A, B in this case are series connected. One may, by way of example, select the ratio of the transformers as follows.

$$\mu_A = 1:1$$

$$\mu = 2:1$$

The impedance of the network between the terminals 5, 6 is in this case

$$\frac{k + k}{2 + 2} = k$$

The impedance k between the input terminals 1, 2 of the network according to Figures 12, 13 is constant at all frequencies as in a network, by way of example according to Figure 11, in which there is no joining of the external terminals of the two filter chains. Between the terminals 3, 4 in Figures 12, 13 the impedance will be constant only at frequencies outside the range of frequencies of the filter chains which is related to the fact that the voltages between the external terminals of the two filter chains, counted from this side, are mutually displaced a phase angle of 180° . If the connections between the terminal couples are shifted the conditions are reversed, i. e. the impedance between the terminals 3, 4 will be constant at all frequencies whereas the impedance between the terminals 1, 2 will be constant only at the frequencies outside the range of frequencies of the filter chains.

In certain cases, by way of example in cascade coupling of several networks, it is of great importance that the impedance both on the input side and on the output side re-

mains constant. In the arrangement according to Figure 14 this is attained by connecting together two networks I, II which each are individually composed according to Figure 11. The network I consists accordingly of two filter chains A, B and the network II of two similar filter chains A', B'. The connecting together of the two networks takes place by joining the external terminals 5, 6 and 7, 8 in the filter chains A, B to the corresponding external terminals 5', 6' and 7', 8' in the filter chains A', B'. The four filter chains A, B, A', B' included in the composed network are all dimensioned for the same range of frequencies. If the oscillation energy is supplied to the input terminals 1, 2 of the network I, it will be transferred under equal distribution to the two terminal couples 5', 6' and 7', 8' to the other filter chain whereas, on the other hand, the voltage between the output terminals 3, 4 of the net I will be zero. The winding directions in the transformers T_A and T are assumed to be so selected that the oscillations incoming to the filter chain II from two sides and having mutually equal energy compensate the mutual effects in relation to the input terminals 1', 2' of the network II whereby the voltage between the latter will be zero whereas the oscillation amplitudes are added as regards the output terminals 3', 4' of the filter chain II. As the oscillations from the one network to the other is transferred completely symmetrical as regards the input terminals 1, 2 and the output terminals 3, 4 of the network I, the impedance between the terminals of said two terminal couples will be constant at all frequencies. To render possible a connecting together of the different filter chains without energy losses the ratio of the transformer T_A , T , T_A' , T' , counted in the direction towards the external terminals of the filter chains, must be so selected that

$$\frac{\mu_A'}{\mu_A} = \frac{\mu_B'}{\mu_B}$$

where μ_A , μ_A' and μ_B , μ_B' designate the ratios of the filter chains A, A', B, B' respectively. To make the impedance between the terminals 1, 2 and 3, 4 equal to k and the impedance between the terminals 3', 4' equal to k' and k , k' constant at all frequencies, it is required that

$$Z_A = \frac{k}{2} \quad Z_A' = \frac{k'}{2}$$

$$Z_B = 2k \quad Z_B' = 2k'$$

where Z_A , Z_A' , Z_B , Z_B' , denote the impedances at the internal terminals of the filter chains A, A', B, B' at the middle frequency of the frequency range. A similar network composition acts thus between its terminals 1, 2 and 3', 4' and between the terminals 1', 2' and 5', 6'.

and 3, 4 or vice versa as an ordinary band filter. Between the terminals 1-2 and 3-4, 1-2 and 1'-2', 3-4 and 3'-4' the network acts as a band suppression filter for said 5 range of frequencies of the filter chains. Thereby that the impedance both between the terminals 1, 2 and between the terminals 3, 4 is independent of the frequencies, several 10 similar network compositions may be series connected without having any mutual disturbing influence.

In Figure 15 there is shown another embodiment and combination of the arrangements described with reference to Figures 15 12 and 14. The two filter chains A and B are substantially built in a manner similar to that described in conjunction with the above networks. By taking certain measures it is attained with only one network 20 is required to attain the same result as in the arrangements according to Figure 14. The network consists of two filter chains A, B dimensioned for the same range of frequencies, each having a ratio of transformation μ_A , μ_B , counted towards the external terminals, μ_B being then equal to $4\mu_A$ and the impedance between the internal terminals of the filter chain A being

$$30 \quad Z_A = \frac{k}{2}$$

and the impedance of the filter chain B being $Z_B = 2k$ where k denotes the impedance between the terminals 1, 2 and 3, 4 at the mean frequency of the frequency range. The secondary winding of the transformer T_1 is divided into equal parts and the middle point a is connected to the terminals 6 of the filter chain B. Said compensating 40 arrangement may also be obtained by that the condenser C_s is divided into two equal series connected condensers the middle point a being branched off between the two condensers. Besides the terminals 1, 2 and 3, 4 the network is further provided with two terminal couples 1', 2' and 3', 4', of which 1' is connected to the terminals 7, 2' and 4' to the terminal 5, and 3' to the terminal 8. If a voltage V_1 having a frequency within the 50 frequency range of the filter chains is impressed upon the input terminal 1, 2 of the network the voltage between the terminals 5, 6 will be, as understood from the preceding equal to

$$55 \quad 2V_1M_B = 2V_1 \frac{M_A}{4} = \frac{V_1M_A}{2}$$

and the voltage between the terminals 7, 8 will be $M_A V_1$. The voltage between the 60 terminals 3, 4 and 1', 2' is zero. The voltage between the point 8 and a becomes thus

$$\frac{M_A V_1}{2}$$

65 and the voltage between the terminals 3', 4'

will be equal to $M_A V_1$. The network has ordinary band filter operation between the terminals 1, 2 and 3', 4' as well as between the terminals 3, 4 and 1', 2'. Between the terminals 1-2 and 3-4, 1-2 and 1'-2', 1'-2' and 3'-4', and 3-4 and 3'-4' all frequencies within the frequency range are suppressed. By shifting the connecting lines at the terminals 5, 6 band filter operation is obtained between 1, 2 and 1', 2', and 75 3, 4 and 3', 4', and band suppression operation between 1-2 and 3-4, 1-2 and 3'-4', 1'-2' and 3'-4', and 1'-2' and 3-4. If the network, as in the preceding example, is so dimensioned that the impedance between the input and output terminals 1, 2 and 3, 4 is equal to k the impedance between the terminals 1', 2' and 3', 4' will be equal to $\mu_A 2 k$. According to the 80 invention k is constant at all frequencies. 85

In Figure 16 an example is shown how the network, described in connection with Figure 15, is arranged when connecting sender and receiver for high frequency telephony to an ordinary telephone line. The arrangement is composed of five series or cascade connected networks I, II, III, IV and V. The network composition is, on the one side, between the terminals 3_v, 4_v connected to a common line L and on the 95 other side terminated by a terminal impedance k . As the impedance between the terminals 3_v, 4_v is constant at all frequencies the line L may obtain a reflectionless termination at all frequencies. Each one of the 100 different networks I to V is made according to Figure 15 and the series connection of the network may take place without energy losses or reflections because the impedance between the input and output terminals of each network is constant at all frequencies. To the terminals 1_i'-2_i', 1_{ii}'-2_{ii}', etc. impedances R_i , R_{ii} are connected. To the terminals 3_i', 4_i' of the network I a low frequency line LF is connected. 110

The terminals 3_{ii}', 4_{ii}', and 3_{iv}', 4_{iv}' of the networks II and IV are each connected to a sender S_{ii} and S_{iv} respectively for high frequent signals and the terminals 3_{iii}', 4_{iii}' and 3_v', 4_v' of the networks III and V are each connected to one receiver M_{iii} and M_v for high frequency signals. If the different networks are dimensioned each for one frequency range they may thus, according to the above, operate simultaneously over the same line L without disturbing each other. Signals incoming from the line L of different frequency are each received by one receiver. Low frequent signals pass with only a negligible attenuation through the network V, IV, III, II and are received by the network I, from the terminals 3_i', 4_i' of which they are forwarded to the line LF. High frequent signals within dif- 115 120 125 130

ferent frequency ranges are received by the networks V, III the signals designated for the latter network passing through V and IV with only a negligible attenuation and 5 without disturbing the receiver M_V . Signals of such frequencies which do not fall within the frequency range of one of the networks pass towards the terminal impedance k in which they dissipate. From LF, S_{II} and S_{IV} 10 signals within different frequency ranges are sent to the line L. Signals incoming from the line LF to the network I are so directed thereby that they pass only to the right through the remaining networks II, 15 III, IV and V to the line L and not to the left to the terminal impedance k . In the same manner high frequency signals are sent from S_{II} and S_{IV} . A signal sent by 20 way of example from S_{II} passes through the filter chains of the network II over its terminals 3_{II} , 4_{II} through III, IV and V to the line L. The directional action in conjunction with the filter action of the filter chains bring about that no energy passes through 25 the network I to the left.

In loading a line it is, as known, desirable to attain a so high loading as possible to reduce thereby the attenuation as far as possible. As, however, the limiting frequency of the line decreases according as the loading is increased and because thereby the rising or falling part of the characteristic curve more and more is displaced downwards towards the speech frequency range. 30 The range for constant characteristic is, upon an increase of the loading, reduced, whereby the speech transmission gets bad. The degree of loading is thus rather limited. By the embodiment of the invention as 35 shown in Figures 17 and 18 a considerable increase of the loading is, however, rendered possible independently of said displacement of the characteristic curve. This is obtained by making the loaded line to 40 form or to be included as a part in the one filter in the impedance network whereas the line or apparatus having constant characteristic is connected to the input terminals of 45 the impedance network. The latter line or apparatus may thus be connected reflection- 50 less to the loaded line.

According to the invention the impedance network is preferably formed in conjunction with a differential transformer, of 55 which the two mutually symmetrical terminal couples form the input terminals of the network or the terminals of a line balance whereas the one of the two other terminal couples of the differential transformer, by 60 way of example, the terminals of the un- 65 divided transformer winding, are connected to the pupinized line and the other, by way of example the middle tappings, are connected to a filter, the characteristic of which 65 varies with the frequency in a manner op-

posite to that of the loaded line. If thus the characteristic of the loaded line is rising the characteristic of the other filter should be falling and vice versa. The geometrical mean of the characteristics of the two filters 70 being then, according to the invention, constant for different frequencies. Also the other filters may advantageously be made of a loaded line the invention thus rendering possible the reflectionless connection of a 75 quad connection consisting of two loaded lines to a two-wire connection having a constant characteristic.

One embodiment of such a connection is 80 shown in Figure 17, the two talking paths in the quad wire connection being used for mutually opposite talking directions, whereas in the connection shown in Figure 18 85 the two lines in the two-wire connection are parallel connected and form together a single talking path.

The differential transformer T serving as 90 connecting element between the lines is connected by its mutually symmetrical terminal couples 1, 2 and 3, 4 respectively on the one side to the free overhead line L and on the other side, to a line balance B having the same impedance as the overhead line L. To the middle tapping of the differential transformer the one loaded line L_1 is connected whereas the other loaded line L_2 is connected to the undivided winding of the differential transformer. The one loaded line L_1 is, adjacent to the differential transformer, terminated by an undivided line 100 section, i. e. a line portion having a length equal to an entire coil distance s , and a load coil P connected thereto, the inductance of which is half as high as the inductance of the load coils P out on the line. Said loaded line represents thus a T-filter i. e. a filter 105 having a falling characteristic. The other loaded line L_2 is adjacent to the differential transformer terminated by a half loaded section of the length 110

$$\frac{s}{2}$$

and represents a π -filter, i. e. a filter having rising characteristics. If the two lines otherwise are similar and loaded with equal load coils P and geometrical means of their characteristics, counted from the differential transformer, will be constant. Said geometrical means should, according to the invention, be or, by suitably disposed line extensions, be made equal to the impedance of the line balance B. The input characteristic of the network consisting of the differential transformer together with the loaded line L_1 120 and L_2 between the terminals 1, 2 is under said condition constant and equal to the characteristic of the line balance. 125

The two loaded lines are assumed to form, in the shown embodiment, each one talking 130

path in the quad wire connection and include each one amplifier V_1 , V_2 for the corresponding talking directions, each of the two lines being adjacent to the appertain-
5 ing amplifier, terminated in the same manner as next to the differential transformer. The line L_1 is thus terminated by an undivided line section s and a thereto connected load coil P having half the normal inductance
10 whereas the line L_2 is terminated by a half line section

s

2

15 In the connection shown in Figure 17 the load coils on the one line in the quad wire connection are displaced half a section distance in relation to the coils in the other line which involves certain practical inconven-
20 iences and results in increased costs of execu-
25 tion. Said inconvenience may, however, be eliminated without difficulty by providing the one of the two pupinized lines adjacent to the differential transformer with a line extension representing a corresponding dis-
placement of the two lines in relation to each other. An embodiment of this kind is shown in Figure 18 where the load coil P of the two loaded lines are disposed opposite each other.
30 The line L_2 is connected to the differential transformer T in the same manner as in Figure 17, i. e. it is terminated adjacent to the differential transformer by a half line sec-
35 tion

s

2

The line L_1 is also terminated with half a line section which, however, is provided with a line extension F . Said line exten-
40 sion consists of a shunt condenser C , connect-
45 ed into circuit next to the line and having a capacity corresponding to the line capacity of half a line section, and a series inductance p the size of which is equal to half the induc-
50 tance of the load coils P on the line. If de-
sired, the line extension may also enclose series resistances R , corresponding together to half the ohmic resistance pro line section.
55 By the addition of the line extension F the line L_1 functions, counted from the differential transformer, in exactly the same man-
60 ner as the corresponding line in Figure 17, i. e. as a T -filter.

55 The quad wire connection is by its op-
posite end connected in similar manner to another overhead line L' or an apparatus having constant characteristic which connection is mediated by a differential trans-
60 former T' of the same kind as the trans-
former T and provided with a corresponding line balance B' . The connection of the two loaded lines to the differential transformer T' is, however, reversed in relation to the connection of T as the line L_2 at T' is termi-
65 nated by a line extension F' and connected

to the middle tapping of the differential transformer whereas the line L_1 instead is connected without line extension to the undivided winding of the differential trans-
70 former. The elements C' , p' , and R' of the line extension F' are the same as the corre-
sponding elements in F . Both lines proper terminate by a half section length $\frac{s}{2}$. In

75 Figure 18 the two lines L_1 , L_2 are evidently entirely equivalent and may form in com-
mon a single talking path consisting of the two lines in parallel connection. In spite
80 of the fact that four lines are used for the transmission of speech current in only one direction the composed line will, however, not be considerably more expensive than a single line because the combined line sec-
85 tional area may be maintained equal to the line sectional area of an ordinary two-wire loaded line without increasing the total at-
90 tenuation or cross talk. Said fact may be concluded from the following reasoning. The attenuation pro kilometer of an ordinary double line is, as known,

$$\beta = \frac{R}{2Z} + \frac{GZ}{2}$$

95 where R is the ohmic resistance per kilo-
meter, Z the line characteristic, and G the leakage per kilometer.

100 The second term on the right hand side in the formula may be neglected because G is very small, only about 10^{-6} , and the term in question may, even in the worst case, represent at most about three percent of the total attenuation per kilometer. From the above formula we make the conclusion that the quantity R may be doubled without in-
105 creasing the attenuation β , provided Z is simultaneously doubled. The cross talk in cables is, as known, substantially a function of the voltage which in turn is $V=ZI$ where I is the amperage. As in this case the current in each line is reduced to one half, one may thus make the characteristic Z twice as high as normally without alter-
110 ing the voltage V and each line L_1 , L_2 may thus be loaded to a characteristic twice as high as that of an ordinary line without, however, increasing the cross talk. If one thus doubles R by reducing the area of each of the two lines one half one obtains the same combined area as in an ordinary line.

115 The increase of the number of the load coils may be partially compensated by that a coil without inconvenience may be made with a smaller iron core and a thinner wire. Such a quad wire line does not take up a
120 considerably larger space in a cable than a two wire line. It may namely be twisted as in a spiral cable. The space taken up by a quad wire twisted in this manner in
125 a cable will not be considerably larger than

the space taken up by two wires which are twisted according to the method of Dieselhorst and Martin.

5 A line made according to Figure 18 is particularly suitable to be used in long distance telephony or for the transmission of music.

We claim:—

1. An electrical network comprising in combination a filter B having its terminals of the one side connected with one input terminal and one output terminal of the network and including an impedance 11, 12 shunted between said terminals, a quadri-pole 17 having one of the terminals on the one side connected to a middle tapping on said impedance and the other terminal of the same side connected with one input terminal and one output terminal of the network, the two halves of the said impedance forming two parallel branches of a series impedance of a second filter A including the said quadripole, the mean squares of the characteristics of said two filters on the sides 20 at which they are associated with one another being independent of the frequency.
2. An electrical network comprising in combination a filter including an impedance shunted between its terminals on one side, 30 said impedance being provided with a middle tapping and forming a series impedance of the network, an artificial line connected between the symmetry points of the two branches of the network, said impedance of the said filter forming two branches of a series impedance of a second filter including said artificial line, the mean squares of the characteristics of said two filters on the sides at which they are associated with one another being independent of the frequency.
3. An electrical network comprising in combination an impedance having a middle tapping and forming a series impedance of the network, a first artificial line connected 40 with one pair of terminals to the ends of said impedance, a second artificial line connected with one terminal to the middle tapping of said impedance and with the other terminal of the same side to one input terminal and one output terminal of the network, said impedance forming together with the first artificial line a first filter while the two halves of said impedance form parallel branches of a series impedance of a second filter including the second artificial line, said filters accordingly having π -characteristic and T -characteristic respectively, on the sides at which they are associated with one another, the mean squares of said characteristics being independent of the frequency.

4. An electrical network comprising in combination a differential transformer connected between one input terminal and one output terminal of the network, a first filter

connected to the one side of said differential transformer, a second filter connected with one terminal to the middle point of the transformer and with the other terminal of the same side to one input terminal and one output terminal of the network, the mean square values of the characteristics of said filters on the sides associated together being substantially independent of the frequency.

5. An electrical network as claimed in claim 1, characterized in that the filters associated therein are so dimensioned that their characteristics at the ends at which they are associated with one another are $\frac{k}{2}$ and $2k$ respectively at the middle frequency within the frequency range of the filters, whereby the impedance between the input terminals and between the output terminals of the network will be equal to k ; said quantity being a constant.

6. An electrical network as claimed in claim 1, characterized in that the complex propagation constants of the filters associated therein have the same value at all frequencies.

7. An electrical network as claimed in claim 1, characterized in that the filters are provided with end impedances which are constant or substantially constant and so selected that the reflections at said impedances substantially compensate each other.

8. An electrical network as claimed in claim 1, characterized in that the end impedances of the filters are so chosen as to establish substantially reflectionless connections at the end terminals of the filters.

9. An electrical network as claimed in claim 1, characterized in that the geometrical means of the characteristics of the two filters at the ends at which they are associated is substantially equal to the impedances connected to the input and output terminals of the network.

10. An electrical network as claimed in claim 1, characterized in that a transmission line is connected to the network on the one side and a corresponding line balance is connected to the network on the other side, sending and receiving apparatuses being connected to the free ends of the two filters.

11. An electrical network comprising in combination a filter having its terminals of the one side connected with one input terminal and one output terminal of the network and including an impedance shunted between said terminals, a quadripole having one of the terminals on the one side connected to a middle tapping on said impedance and the other terminal of the same side connected with one input terminal and one output terminal of the network, the two halves of the said impedance forming two parallel branches of a series impedance of 125

a second filter including the said quadripole, the mean squares of the characteristics of said two filters on the sides at which they are associated with one another being independent of the frequency, and transformers being included in the filters, said transformers having their ratio of transformation so chosen as to transmit an incoming oscillation with equal voltages to the end impedances of the filters.

12. An arrangement as claimed in claim 11, characterized in that the ratio of transformation in the filter commencing with a shunt impedance is one half of the ratio 15 of transformation in the other filter.

13. An arrangement as claimed in claim 11, characterized in that the two filters are joined in series connection at their free ends.

14. An arrangement as claimed in claim 20 11, characterized in that the two filters are joined in parallel connection at their free ends.

15. A circuit arrangement composed of two networks, as claimed in claim 11, said 25 networks being connected in such a manner that the external terminals of mutually corresponding filter chains are connected to each other.

16. An electrical network as claimed in 30 claim 11, characterized in that the filter having T-characteristic includes a differential device the middle point of which is connected to the one end terminal of the other filter, and that by the connection between the filters there are formed two terminal 35 couples and from each one of the end terminals of the filter first mentioned and the free end terminal included in common in the two terminal couples in the other filter.

17. An electrical network as claimed in 40 claim 1, characterized in that the two filters associated therein are composed of equal numbers of impedances corresponding to each other two and two in such a manner 45 that the mean square of the two impedance values of each pair is equal for all pairs of the impedances.

18. An electrical network as claimed in 50 claim 1, characterized in that the two filters associated therein are composed of equal numbers of impedances, each shunt impedance in the one filter corresponding to a series impedance in the other filter in such a manner that the mean square of two cor-

responding impedances is equal for all pairs of corresponding impedances.

19. A circuit arrangement composed of a number of cascade coupled networks according to claim 1, said networks being dimensioned for different frequency ranges. 70

20. A circuit arrangement composed of a number of cascade coupled networks according to claim 1, said networks being connected at one end to a transmission line and at the 75 other end to a corresponding line balance, and sending and receiving apparatuses being connected to the two filters associated in each of the networks.

21. An electrical network comprising in 80 combination a filter having its terminals of the one side connected with one input terminal and one output terminal of the network, a quadripole having one of the terminals on the one side connected to a symmetry point of said filter and the other terminal of the same side connected with one input terminal and one output terminal of the network, the mean square of the impedance between said terminals of the filter on 85 the one hand and on the other hand the impedance between said terminals in parallel connection and the opposite terminal of the quadripole on the side associated with the filter is independent of the frequency. 90

22. An electrical network as claimed in claim 1, characterized in that the two filters associated therein are composed of equal numbers of impedances, each shunt impedance in the one filter corresponding to a 100 series impedance in the other filter, and that the mutually corresponding impedances are built up each of an equal number of part impedances in such a manner that the product of each part impedance of the one filter 105 and the corresponding part impedance of the other filter is substantially constant at all frequencies.

23. An electrical network as claimed in claim 1, characterized in that the two filters 110 associates therein are composed of equal numbers of impedances, each shunt impedance in the one filter corresponding to a series impedance in the other filter, and that induction coils included in the corresponding 115 impedances are dimensioned for the same loss angle.
